F. T. MADSEN

MEASURED SERVICE TELEPHONE SYSTEM

Filed May 5, 1923

— Inventor —
Fred T. Madsen

Charles Candy, Atty.

UNITED STATES PATENT OFFICE.

FRED T. MADSEN, OF MAYWOOD, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

Application filed May 5, 1923. Serial No. 336,836.

To all whom it may concern:

Be it known that I, FRED T. MADSEN, a citizen of the United States of America, and a resident of Maywood, Cook County, 5 and State of Illinois, have invented certain new and useful Improvements in Measured-Service Telephone Systems, of which the following is a specification.

The present invention relates in general 10 to measured service telephone systems, but is concerned more particularly with improved circuits for controlling measured service apparatus for use in automatic telephone systems.

15 The principal object of the invention is to provide novel and efficient circuit arrangements for use in controlling paystation equipment of the type in which the calling subscriber is not required to deposit the 20 coin or token until the called subscriber responds.

Another object is to arrange the above 25 circuits so that no additions or changes need be made in the switchhook spring combination of the standard substation apparatus.

A still further object is to provide an arrangement of circuits which will cause the 30 operation of the pay station magnet when a called subscriber answers, but which cannot be restored by the called subscriber again 35 operating his receiver hook.

In the accompanying drawing are shown 40 diagrammatically only such circuits of an automatic telephone system as are considered necessary to clearly illustrate the invention. The substation A is provided with the usual receiver 20, transmitter 9, switchhook 21, induction coil 22, and signalling device 23. Being an automatic substation, 45 there is also provided the usual calling device C. D.

The paystation apparatus PS associated 50 with the substation A is of similar construction to that shown and described in Patent 1,225,603, issued to John Erickson May 8, 1917. The only difference being that an additional pair of springs have been added, which springs are closed when the called subscriber responds but are not arranged 55 to be opened when a coin is deposited.

The two line conductors 1 and 2 extend 60 to the exchange, where they terminate preferably in an individual line switch or trunk

selector C, of which only the two line wipers are shown herein. The line switch C may 55 be of any approved type and is operable upon the closure of the line circuit at the substation A to extend the line conductors 1 and 2 into connection with a trunk line terminating in a numerical selector or connector switch, as the case may be, depending 60 on the size of the exchange. For the sake of simplicity, no selector switches have been indicated in the drawing, it being assumed 65 that the line switch C has direct access to a connector switch H which in turn has access to a group of subscribers' lines, one of which is the line of substation A'. The connector H, like the line switch C, may be of any approved two wire type, its 70 only essential characteristic being the provision of means whereby, upon the response of the called subscriber, the incoming line conductors are reversed as regards their connection to the windings of the line or 75 controlling relay. Thus in the connector shown the line conductors 1 and 2 before terminating in the windings of the line relay 3, pass through reversing springs on the back bridge relay 4. Line, selector, and connector switches of suitable construction are shown in U. S. patent to Newforth, Reissue No. 13,901, dated April 13, 1915.

To proceed with the description of operation, it will be assumed that the subscriber at substation A desires to obtain 85 connection with the subscriber at substation A'. Upon the removal of the receiver at substation A, a circuit is closed over which current from the exchange battery (which is 90 normally bridged across the line conductors 1 and 2 in series with the line relay of the line switch C) flows as follows: Line conductor 1 on the right of the condenser 6, winding 24 of the polarized magnet 5, back 95 to line conductor 1 on the left hand side of the condenser 6, impulse springs 7 of the calling device C. D., switchhook springs 8, transmitter 9, primary winding of the induction coil 22 to line conductor 2. By the 100 closure of this circuit the line switch C is operated to extend the line conductors 1 and 2 to the line relay of an idle connector H. The removal of the receiver also closes the 105 receiver circuit, which is a local circuit including the switchhook, the receiver 20,

transmitter 9, springs 8, springs 7, the condenser, and the secondary winding of the induction coil 22.

It will be recalled that the left hand 5 winding of the polarized magnet 5 was also included in the above described circuit. This magnet is not energized at this time, due to the normal current flow being in the wrong direction.

10 The calling subscriber may now proceed to manipulate the dial of his calling device C. D. in accordance with the digits of the number of substation A', whereby the connector H is operated in the usual and well 15 known manner to complete the desired connection, it being assumed that the line of substation A' is not busy at the time. During the operation of the calling device the shunt springs 10 are closed to short circuit 20 the receiver and the transmitter. This is the usual provision made to reduce the resistance and impedance of the line circuit during the transmission of impulses, and to prevent noises in the receiver.

25 Assuming that the called subscriber responds to the call, when the receiver is removed the substation A' is supplied with talking battery through the windings of the back bridge relay 4. This relay is therefore energized to reverse the line conductors 30 1 and 2 as regards their connection to the windings of the line relay 3. Current now flows over the line circuit and through the winding 24 of the polarized magnet 5 in the reverse direction. This reversal of the current causes the polarized relay of the coin collecting device at substation A to attract 35 its armature in the opposite direction, that is, toward the coil 24. When the armature is 40 attracted in this direction it carries the arm 13 to the right, forcing the springs 14, 15 and 16 into engagement. The armature itself 45 also closes springs 19. The engagement of springs 14, 15, and 16 short circuits the transmitter, and connects the resistance 17 50 in shunt with the primary winding of the induction coil 22. The short circuiting of the transmitter 9 makes it impossible for the calling subscriber to talk to the called 55 subscriber through the medium thereof. The shunting of the primary winding of the induction coil 22 does not prevent the calling subscriber from hearing the called subscriber answer, but does not allow him to converse 60 through his receiver. When the calling subscriber hears the called subscriber answer 65 he deposits a coin in the coin chute. This coin, in passing down the chute, releases the arm 13 from the arm 12, thereby allowing the springs 14, 15 and 16 to separate. The separation of these springs leaves the talking circuit for the calling substation in normal condition, and the two subscribers may converse over the circuits represented by the 65 heavily drawn lines. It will be noted that

since springs 19 are controlled directly by the armature 11, that they will not be affected by the deposit of the coin. The purpose of these springs will be brought out subsequently.

Should the called subscriber for any reason operate his switchhook after he has answered, resulting in the original current flow being again established as regards lines 1 and 2, the polarized magnet 5 will not be 70 affected, as the tension of the spring 18, and the sharp angle of the catch, or incline on the arm 13 act to prevent the armature from being restored by the energization of winding 24 of the magnet. It will be seen that 75 this arrangement is very essential, as some subscribers may attempt to signal an operator by jiggling the switchhook were the above means not provided, the springs 14, 15 and 16 would be again closed and the calling subscriber would have to deposit a second coin before conversation could be continued.

80 After the conversation is completed, the release of the central office apparatus is initiated in well known manner, by the hanging up of the receiver at the calling substation.

85 It will be recalled that when the called subscriber responded that the operation of the magnet 5 resulted in the closure of springs 19. The closure of these springs completed a circuit extending from line conductor 1 at the right of condenser 6, springs 19, winding 25 of the polarized magnet 5, 90 transmitter 9, and the primary winding of the induction coil 22 to line conductor 2. This circuit is for restoring the paystation apparatus to normal, and is not effective 95 while the receiver is off the hook at the station A, as winding 25 is partially short circuited by a circuit extending through the relatively low resistance of winding 24 of the magnet 5. This shunt circuit may be traced from line 1 at the right of condenser 6, 100 (low) winding 24 of magnet 5, line 1 at left of condenser 6, calling device springs 7, switchhook springs 8, (high) winding 25 of magnet 5, and contacts 19 back to line 1. 105

110 Now when the calling subscriber replaces his receiver the shunt circuit around winding 25 is removed. Since the winding 25 is very high the line relay 3 of the connector cannot remain energized, and this relay in restoring causes the usual circuit for releasing the connector H to be completed, and also causes the line switch C to restore the normal exchange battery to line conductors 1 and 2. 115

120 This normal exchange battery will now energize winding 25 of the magnet 5 to restore the arm 12 into its normal position at the left of the catch on arm 13, and also to break its own circuit at contacts 19.

125 Having described the invention, what is considered new and is desired to have pro-

tected by Letters Patent will be pointed out in the appended claims.

What is claimed is:

1. In a telephone system, calling and called lines, means including automatic switches for interconnecting said lines, paystation mechanism associated with the calling line, said paystation mechanism being provided with a polarized relay, said polarized relay having a high impedance winding and a low impedance winding, contacts in the calling telephone operated by the removal of the receiver for completing a circuit for one winding of said polarized relay, means effective when the called subscriber removes his receiver to cause current to flow through said relay in the proper direction to operate it, contacts on said relay closed when the same is operated to complete an operating circuit through the other winding of said relay, and means for making said last circuit ineffective while the calling subscriber has his receiver off the hook.

2. In a telephone system, calling and called lines, means including automatic switches for interconnecting said lines, paystation mechanism associated with the calling line, said paystation mechanism being provided with a polarized relay, said polarized relay having two windings, contacts in the calling telephone operated by the removal of the receiver for completing a circuit for one winding of said polarized relay, means effective when the called subscriber removes his receiver to cause current to flow through said relay in the proper direction to operate it, contacts on said relay closed when the same is operated to complete an operating circuit through the other winding of said relay, and switchhook springs for maintaining the operating circuit of said other winding shunted by the said first winding to prevent the restoring operation of said magnet while the receiver is off the hook.

3. In a telephone system, calling and called lines, means including automatic switches for interconnecting said lines, paystation mechanism associated with certain of said lines, said paystation mechanism being provided with a polarized relay having an operating and a restoring winding, contacts in the telephones of said lines operated by the removal of the receiver at the substation for completing a circuit for the operating winding of the said polarized relay, means effective when the called subscriber responds to cause current to flow through the operating winding of said relay in the proper direction to operate it, and contacts on said relay closed when the same is operated to complete a circuit through the restoring winding of said relay and for making said last circuit ineffective by connecting said operating

winding in multiple therewith while the calling subscriber has his receiver off the hook.

4. In a telephone system, calling and called lines, means including automatic switches for interconnecting said lines, paystation mechanism associated with certain of said lines, said paystation mechanism being provided with a polarized relay having an operating and a restoring winding, contacts in the telephones of said lines operated by the removal of the receiver at the substation for completing a circuit for the operating winding of said polarized relay, means effective when the called subscriber responds to cause current to flow through the operating winding of said relay in the proper direction to operate it, and contacts on said relay closed when the same is operated to complete a circuit thru the restoring winding of said relay and for making said last circuit ineffective by connecting said operating winding in multiple therewith while the calling subscriber has his receiver off the hook, the replacement of the receiver being effective to open the circuit extending thru said operating winding to permit the circuit extending thru the restoring winding to be effective.

5. In a telephone system, calling and called lines, automatic switches for connecting said lines, paystation mechanism on the calling line including a magnet having means for rendering the talking equipment on the calling line ineffective when the battery is reversed therethrough, another magnet normally inoperative, means controlled by the first magnet for closing a circuit for the other magnet, a shunt around said other magnet for preventing its operation, and means controlled by the restoration of the receiver at the calling station for removing said shunt to cause said other magnet to operate to prepare said first magnet for further operation.

6. In a telephone system, calling and called lines, means for connecting said lines, paystation equipment on the calling line comprising a pair of magnets, one of said magnets operated by the response of the called subscriber for shunting the talking equipment on the calling line and for closing a circuit for the second magnet, means controlled by the deposit of a coin in said mechanism for removing the shunt from the talking equipment and rendering the first magnet ineffective, a shunt around the second magnet preventing its operation, and means controlled by the restoration of the receiver at the calling station for opening said shunt, said second magnet operated in response to the opening of said last shunt to again render the first magnet effective.

In witness whereof, I hereunto subscribe my name this 2d day of May, A. D., 1923.

FRED T. MADSEN.
